UNITED STATES PATENT OFFICE.

JAMES J. TRACY, OF CLEVELAND, OHIO.

CARBURETER.

1,222,162

Specification of Letters Patent. Patented Apr. 10, 1917.

Application filed July 28, 1914. Serial No. 853,654.

To all whom it may concern:

Be it known that I, JAMES J. TRACY, a citizen of the United States, and a resident of Cleveland, county of Cuyahoga, and State of Ohio, have invented a new and useful Improvement in Carbureters, of which the following is a specification, the principle of the invention being herein explained and the best mode in which I have contemplated applying that principle, so as to distinguish it from other inventions.

The object of the present invention is to provide a charge-forming device, or carbureter, of simple construction yet capable of the various adjustments necessary to insure the proper proportion of air and fuel, as also to insure the thorough intermixture of these constituents of the charge. To the accomplishment of the foregoing and related ends, the invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Figure 1 is a longitudinal vertical section of the device proper with the associated float chamber; Fig. 2 is a plan view of the same; Fig. 3 is a transverse vertical section of such device taken on the plane indicated by the line 3—3, Fig. 1; Fig. 4 is a longitudinal vertical section of a modified construction of the device; Fig. 5 is a horizontal section of such modified construction; and Fig. 6 is a side elevation of a detail.

Referring, first of all, to the form of construction illustrated in the first three of the above named figures, the fuel discharge nozzle 1, it will be observed, projects inwardly from the wall of a cylindrical casing 2 in an upwardly inclined direction, being provided with a downwardly directed discharge opening 3, as well as with a discharge opening 4 aligned with a central bore 5 through which the fuel is designed to be supplied to the device. The height of the fuel in the nozzle is regulated by a float 6 in a float chamber 7 arranged to actuate a valve 8 in the supply line 9 through the medium of a lever 10 in the usual way.

The end opening 4 in the nozzle 1 is normally closed by a needle valve 11 fitted there-

to, the stem of such valve having threaded engagement in the opposite wall of the casing, so that the valve will be moved toward or from the nozzle upon being rotated. A 60 spring plunger 12 mounted in an arm projecting from the casing is adapted to engage notches in a disk 13 fixed on the stem of the valve so as to retain the latter in whatever position it may be left.

Interiorly threaded in the lower portion of the casing 2, below the nozzle 1, is a cylindrical shell 14 that is open at its upper end but closed at its lower, so as to at the same time close such casing end. By reason of 70 its threaded engagement, not only may this shell be rotated, but such rotation will produce a longitudinal movement of the shell relatively to the casing. A needle valve 15 for controlling the downwardly directed discharge opening 3 of the nozzle has its stem centrally threaded in the lower end of this shell. Such valve, upon being initially set in desired vertical relation to the shell, is secured in such position by a lock nut 16 on the projecting portion of the stem. Rotation of the shell may be produced by means of a lever 17, so as to lower the valve and thus open the downwardly directed nozzle opening a variable amount.

Formed directly below the needle valve proper on the stem which supports the latter is a flaring head 18 with a curved upper face, somewhat resembling a mushroom, which receives the fuel that is discharged 90 through the opening 3 when the valve is thus lowered. Any drippings from this head are designed to be caught on a shelf-like partition 19 in the shell, such partition being located just below a series of openings 20 95 (three as shown) in the side walls of the shell that are adapted in one position of the latter to register with corresponding openings 21 in the casing 2. It will be obvious that the openings 21 are controlled by rotation on the shell 14, at the same time that the nozzle opening 3 is controlled by the longitudinal movement of such shell.

Surrounding the casing 2, so as to be rotatable with respect thereto, is an outer shell 105 22 provided with a lever 23 for convenient operation, and also having apertures 24 adapted to register with those in the casing, so that such last-named apertures may be closed or opened independently of the inner 110 shell.

The mode of operation of my improved

charge-forming device, or carbureter, may now be briefly set forth, it being understood that the upper end of the casing 2 is connected with the usual manifold, or other connection, leading to the engine cylinder or cylinders, and that the fuel in the nozzle 1 is maintained, as already set forth, at or about the level shown in Fig. 1. The needle valve 15 controlling the downwardly directed opening 3 of the nozzle is then lowered by suitably rotating the shell 14 through lever 17, this operation being effected, in the case of an automobile engine, by the hand throttle or foot accelerator. The apertures 21 in the wall of the casing for admitting air into the latter will be simultaneously opened the proper amount. Should it be desired to increase the proportion of fuel to the amount of air thus admitted, the other needle valve 11 may be opened slightly, the amount of such opening remaining unchanged during the running of the engine, and all regulation being secured by adjustment of the first-named valve. In starting, in order that a sufficiently rich mixture may be obtained to prime the engine, as it is called, the outer shell 22 on the casing may be rotated to substantially entirely close the apertures in the latter, despite the open position of the inner shell.

The modification in construction illustrated in Figs. 4, 5 and 6 consists principally in a modified form of shell for controlling the air supply to the casing, and in the substitution of other means for shutting off such air supply in priming the engine. The parts which remain unchanged are designated by the same reference characters as in Figs. 1, 2 and 3, and need not be again described. The inner shell 25, however, it will be observed is designed for reciprocable movement only, such movement being secured by means of a bell crank 26 connected with the lower projecting end of the valve stem 27 (corresponding with valve stem 15), which stem is adjustably held in the shell, passing through spiders 28 with the lower of which it has threaded engagement. A lock nut 29, as before serves to secure such stem in desired position. The shell 25 is provided at its respective extremities with beveled annular surfaces 26 and 27 that are adapted to seat against complementary beveled annular surfaces on the casing, and when thus seated to close lateral openings 30 in the latter corresponding with the apertures 21 in the previously described construction. Upon lowering the shell, however, the casing will be opened a corresponding amount at both the upper and lower ends of the shell, as will be obvious.

In place of the outer shell 22 for closing the openings in the casing in priming the engine, a supplemental casing 31 of the

form clearly shown in Figs. 4 and 5, is fitted over such main casing, thereby providing an annular passageway entirely around the latter of varying cross-section, the largest cross-section being adjacent an inlet opening 32 which is controlled by a butterfly valve 33, and decreasing gradually to a point diametrically opposite. The butterfly valve is prevented from being entirely shut by means of a set-screw 34 (Fig. 6) mounted in a lever-arm 36 on one end of its stem and adapted to engage an opposed shoulder 35 on the casing, such lever having another arm 37 by means of which the stem may be rotated. A spring-pressed plunger 38 in shoulder 35 co-operating with notches on the lever, serves to hold the valve in either its open or closed position.

This second constructional form of the device operates essentially in the same manner as the first form, as need not be again explained. In both forms it will be observed that the major portion of the fuel is discharged downwardly, that is against the incoming air. The fuel as it escapes from the nozzle is received on the upper surface of the flaring head 18 carried by the stem of the valve which controls the downwardly directed nozzle opening. Such head is preferably of fairly large diameter, and has a sharp edge so that the fuel is distributed in as thin a film as possible by the time it reaches such edge and thus is adapted to be more readily picked up by the air. The fuel that is discharged through the aligned opening 4 of the nozzle, will likewise be received on this head 18 if not vaporized sooner. The device is throughout of simple and substantial construction, having no parts that are liable to get out of order.

Since, in running light, it is apt to be difficult to leave just the right amount of opening for the air to correspond with the minimum fuel supply position of valve 15, I may prefer to adjust such valve in shell 14 so that the latter entirely shuts off air-inlet openings 21 in the casing when said valve 15 is thus positioned to supply a minimum amount of fuel. In such case small openings 40 and 41 (Fig. 1) are provided in the bottom of the shell and the partition 19, respectively, the size of these openings being gaged to admit the required amount of air for the purpose specified.

While I have herein referred to the fuel-supply nozzle as being located above the air-inlet openings and as discharging downwardly, I do not mean thereby to limit the construction to one in which the casing 2 is strictly vertical, the essential feature being merely that the fuel should be discharged in a direction opposite to that in which the air moves through such casing. The descriptive terms just referred to should accordingly be understood in this sense.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

- 10 1. In a device of the character described, the combination of a casing having air-inlet openings in its sides; a fuel supply nozzle projecting into said casing from one side at a point beyond such openings having regard to the direction of the flow of air from said openings through said casing, said nozzle being formed with a discharge opening directed oppositely to such direction of air flow; and a needle valve mounted in said casing so as to be reciprocable longitudinally of the same and adapted to control such nozzle opening, said valve being provided just below its point with a flaring head having a convex face directed toward such opening.

2. In a device of the character described, the combination of a casing having air-inlet openings in its sides; a fuel supply nozzle projecting into said casing from one side 20 at a point beyond such openings having regard to the direction of the flow of air from said openings through said casing, said nozzle being formed with a discharge opening directed oppositely to such direction of air 25 flow; a needle valve mounted in said casing so as to be reciprocable longitudinally of the same and adapted to control such nozzle opening, said valve being provided just below its point with a flaring head having a 30 convex face directed toward such opening; and a valve, operable conjointly with said first-named valve, adapted to control such 35 air-inlet openings.

45 3. In a device of the character described, the combination of a casing having air-inlet openings in its sides; a fuel supply nozzle projecting into said casing from one side at a point beyond such openings having regard to the direction of the flow of air from 50 said openings through said casing, said nozzle being formed with a discharge opening directed oppositely to such direction of air flow; a needle valve mounted in said casing so as to be reciprocable longitudinally 55 of the same and adapted to control such nozzle opening, said valve being provided just below its point with a flaring head having a convex face directed toward such opening; and a shell mounted within said casing so 60 as to be movable conjointly with said valve, said shell being adapted to control such air-inlet openings.

4. In a device of the character described, the combination of a casing having air-inlet openings in its sides; a fuel supply nozzle

projecting into said casing from one side at a point beyond such openings having regard to the direction of the flow of air from said openings through said casing, said nozzle being formed with a discharge opening 70 directed oppositely to such direction of air flow; a shell in said casing having threaded engagement therewith so as to be reciprocable longitudinally thereof upon being rotated, said shell being adapted to control 75 such air-inlet openings incidentally to such rotation; and a needle valve carried by said shell and adapted to control such nozzle opening, said valve being provided just below its point with a flaring head having a 80 convex face directed toward such opening.

5. In a device of the character described, the combination of a casing having air-inlet openings in its sides; a fuel supply nozzle projecting into said casing from one side at a point beyond such openings having regard to the direction of the flow of air from said openings through said casing, said nozzle being formed with a discharge opening directed oppositely to such direction of air flow; a shell in said casing having threaded engagement therewith so as to be reciprocable longitudinally thereof upon being rotated, said shell being adapted to control such air-inlet openings incidentally to such rotation; and a needle valve adjustably supported by said shell and adapted to control such nozzle opening, said valve being provided just below its point with a flaring head having a convex face directed toward such opening. 100

6. In a device of the character described, the combination of a casing having air-inlet openings in its sides; a fuel supply nozzle projecting into said casing from one side at a point beyond such openings having regard to the direction of the flow of air from said openings through said casing, said nozzle being formed with a discharge opening directed oppositely to such direction of air flow: a needle valve mounted in said casing so as to be reciprocable longitudinally of the same and adapted to control such nozzle opening, said valve being provided just below its point with a flaring head having a convex face directed toward such opening; a valve, operable conjointly with said first-named valve, adapted to control such air-inlet openings: and yet another valve, independent of both aforesaid valves, adapted to control such air-inlet openings.

7. In a device of the character described, the combination of a casing having air-inlet openings in its sides; a fuel supply nozzle projecting into said casing from one side at a point beyond such openings having regard to the direction of the flow of air from said openings through said casing, said nozzle being formed with a discharge opening directed oppositely to such direction 130

- of air flow; a shell in said casing having threaded engagement therewith so as to be reciprocable longitudinally thereof upon being rotated, said shell being adapted to control such air-inlet openings incidentally to such rotation; a needle valve carried by said shell and adapted to control such nozzle opening, said valve being provided just below its point with a flaring head having a convex face directed toward such opening; and a second shell rotatably mounted on the outside of said casing and adapted to control such air-inlet openings independently of said first-named shell.
- 15 8. In a device of the character described, the combination of a casing having an air-inlet opening; a fuel supply nozzle projecting into said casing so as to lie in the path of flow of the air passing from said opening through said casing, said nozzle having one discharge opening directed oppositely to such direction of flow and a second discharge opening; and needle valves mounted in said casing and independently operable to control such nozzle openings, respectively.
9. In a device of the character described, the combination of a casing having air-inlet openings in its sides; a fuel supply nozzle projecting into said casing from one side at a point beyond such openings, having regard to the direction of flow of air through said casing from such openings, said nozzle having one discharge opening directed oppositely to such direction of flow; a second discharge opening; and needle valves mounted in said casing and independently operable to control such nozzle openings, respectively.
10. In a device of the character described, the combination of a casing having air-inlet openings in its sides; a fuel supply nozzle projecting into said casing from one side at a point above such openings, said nozzle having a downwardly directed and a terminally alined discharge opening; and needle valves mounted in said casing and independently operable to control such nozzle openings, respectively.
11. In a device of the character described, the combination of a casing having air-inlet openings in its sides; a fuel supply nozzle projecting into said casing from one side at a point above such openings, said nozzle having a downwardly directed and a terminally alined discharge opening; needle valves mounted in said casing and independently operable to control such nozzle openings, respectively.
12. In a device of the character described, the combination of a casing having an air-inlet opening; a fuel supply nozzle projecting into said casing and formed with a discharge opening opposed to the direction of flow of air through said casing; and a needle valve adapted to control such discharge opening, said valve being provided, just below its point, with a flaring head, having a convex face directed toward such opening.
13. In a device of the character described, the combination of a casing having air-inlet openings in its sides; a fuel supply nozzle projecting into said casing from one side at a point beyond such openings having regard to the direction of the flow of air from said openings through said casing, said nozzle being formed with a discharge opening directed oppositely to such direction of air flow; and a needle valve mounted in said casing so as to be reciprocable longitudinally of the same and adapted to control such nozzle opening, said valve being provided just below its point with a flaring head.
